UNITED STATES PATENT OFFICE.

MARSHALL H. BIDWELL, OF KANSAS CITY, KANSAS.

DEHORNING-GATE.

No. 821,454.

Specification of Letters Patent.

Patented May 22, 1906.

Application filed January 16, 1906. Serial No. 296,256.

To all whom it may concern:

Be it known that I, MARSHALL H. BIDWELL, a citizen of the United States, residing at Kansas City, in the county of Wyandotte 5 and State of Kansas, have invented certain new and useful Improvements in Dehorning-Gates, of which the following is a specification.

This invention relates to dehorning structures; and my object is to produce an efficient and reliable structure of a character which will accommodate cattle of different sizes and by which the cattle can be quickly caught and held during the dehorning operation and then as quickly released.

To this end the invention consists in certain novel and peculiar features of construction and organization, as hereinafter described and claimed, and in order that it may be fully understood reference is to be had to the accompanying drawings, in which—

Figure 1 is a perspective view of a dehorning structure as arranged in conjunction with a cattle-chute. Fig. 2 is a top plan view of 25 the same. Fig. 3 is a front view with the lever thrown back and with the gate-posts at the outer sides of the chute. Fig. 4 is a section on the line IV IV of Fig. 3.

In the said drawings, 1 2 respectively indicate the latch and hinge posts of the structure connected, by preference, at their lower ends by sill 3 and near their upper ends by cross-bar 4, the front side of the latter, by preference, being flush with the front side of 35 post 1, but rearward of the corresponding side of post 2.

5 indicates a block bolted to the front side of post 1 and preferably equipped with a cushion 6 at its upper end and with a bracket 40 7, projecting from its face, connecting said block 5 with a block 8. Secured to the upper end of post 1 is a bar 9, which bar is connected by a transverse bar 10 to post 2, said bars 9 and 10, in connection with post 1 and cross-bar 4, connecting posts 1 and 2, forming 45 connecting slots or ways which extend at right angles to each other.

11 indicates a gate hinged, as at 12 or otherwise, to post 2, one strap of the upper 50 hinge being preferably extended to form a tongue 13 to project beyond block 5 and engage the bifurcated bracket 7, a pin 14, preferably carried by the bracket, being utilized to secure the tongue 13 in the bracket, and 55 therefore lock the gate closed.

15 indicates a recess in the upper edge of

the gate near its free end, the wall of the recess being covered with rubber or equivalent material 16 to reduce chance of abrasion of the animal's neck. Pivoted to the gate, as at 60 17, at the end of the recess most remote from the post 1, is a neck-lever 18, having an arched portion 19 to fit over the animal's neck just behind the horns, the arch and recess together forming an elliptical opening when the lever is 65 down. Said lever projects normally through the slot or way between bars 4 and 10 hereinbefore referred to and when down through the slot between post 1 and bar 9 and rests upon the cushion 6, which cushion is provided mainly to deaden the sound when the lever is thrown upon it through the medium of the cable 20, said cable when the lever is thrown back, as shown in Fig. 3, engaging a pin 21, projecting laterally from the upper 70 end of post 1.

When the neck-lever is down, it is locked in such position by a pin 22 engaging one of a series of vertical holes 23 in post 1, and said pin is preferably attached to the block 5, so 80 as to be always conveniently at hand by the chain or cable 24.

25 indicates brackets secured to the gate near its hinged end, and journaled therein is the depending arm 27 of a nose-lever 26, 85 adapted to operate in a horizontal plane and having a forwardly-bowed portion 28 opposite recess 15, said bowed portion being adapted to fit over the nose of the animal, and to prevent abrading the nose is preferably covered with a piece of rubber hose 29. When the nose-lever is closed, as shown in Fig. 1, it rests upon the supporting-bracket 30, carried by the gate between the free end thereof and its recess. To secure the lever quickly 90 and reliably in position, a flexible connection, such as chain 31, is secured to the outer side of post 1 to be looped around said lever and then have one of its links slipped over a pin 32, projecting laterally from block 5, or the 100 chain may be coiled around said pin or otherwise reliably anchored to the block for the purpose of preventing the animal from pushing the nose-lever forward.

The dehorning structure described may be 105 fitted and secured between the sides 33 of a cattle-chute or may be fitted and secured to the outer sides of said chute, the special arrangement being unimportant, provided the connection is secure, and in order to prevent 110 the cattle from jumping over the gate in an attempt to escape from the chute I provide a

cross-bar 34, which may be secured in slotted arms 35, secured rigidly to posts 1 and 2, it being obvious that said arms 35 in practice may form the upper rails of the chute, as indicated in Figs. 2 and 3.

In practice the cattle are compelled to pass through the chute, the neck-lever at such time occupying the position shown in Fig. 3, so as to provide a large opening 10 through which the animal may poke his head, the nose-lever at the same time occupying substantially the position shown in Fig. 2. At the instant the animal pokes his head through said opening, the gate attendant, 15 who is grasping cable 20, pulls downward upon the same, so as to swing the neck-lever from the position shown in Fig. 3 to the position shown in Fig. 1, so that the arch of said lever shall fit over the animal's neck and force 20 the same down into the recess 15. The attempt of the animal to withdraw his head being thus frustrated, the operator while thus holding the animal's head in the position described slips pin 22 into the opening 23 next 25 above the lever, it being obvious that the size of the animal's neck will determine into which hole the pin is slipped. The action described is performed in an instant, and then the operator grasps the nose-lever and swings 30 it to the position shown in Fig. 1, so as to fit over the nose and force the head downward in the most convenient position for removing the horns, said lever being secured in the position last described through the 35 instrumentality of chain 31 and pin 32. The operator now removes the horns, usually by sawing them off close to the head. He then effects the release of the nose-lever, withdraws pin 22, and throws the neck-lever up to 40 its original position and at practically the same instant removes pin 14 and swings the gate open to permit the animal to pass through the gateway, it being noticed in this connection that when the neck-lever is in the position 45 shown in Fig. 3 the gate can be opened and closed, because the slot between bars 4 and 10 is sufficiently wide to accommodate the movement of the lever during such operation. Immediately after the animal emerges 50 the gate is reclosed and locked and the other movable elements properly disposed for the reception of the next animal.

From the above description it will be apparent that I have produced a dehorning structure possessing the desirable features of 55 strength, durability, and ease and convenience in operation, which may obviously be modified in minor particulars without departing from the principle of construction involved.

Having thus described the invention, what I claim as new, and desire to secure by Letters Patent, is—

1. A dehorning structure embodying gate- 65 posts having slots or guideways at the upper

end and latch-post side of the gateway, a gate hinged to the hinge-post, and provided with a recess in its upper edge, and a lever hinged to the gate at the side of said recess nearest the hinge-post and adapted to project 70 through either of said slots or guideways and provided with an arched portion at its pivoted end.

2. A dehorning structure embodying gate- 75 posts having slots or guideways at the upper end and latch-post side of the gateway, a gate hinged to the hinge-post, and provided with a recess in its upper edge, a lever hinged to the gate at the side of said recess nearest the hinge-post and adapted to project through 80 either of said slots or guideways and provided with an arched portion at its pivoted end, and means to secure the lever depressed with its arched portion forming an opening 85 in conjunction with said recess. 85

3. A dehorning structure embodying gate- 90 posts having slots or guideways at the upper end and latch-post side of the gateway, a gate hinged to the hinge-post, and provided with a recess in its upper edge, a lever hinged to the gate at the side of said recess nearest the hinge-post and adapted to project through 95 either of said slots or guideways and provided with an arched portion at its pivoted end, and a flexible connection attached to 95 said lever.

4. A dehorning structure embodying gate- 100 posts having slots or guideways at the upper end and latch-post side of the gateway, a gate hinged to the hinge-post, and provided with a recess in its upper edge, a lever hinged to the gate at the side of said recess nearest the hinge-post and adapted to project through 105 either of said slots or guideways and provided with an arched portion at its pivoted end, a flexible connection attached to said lever, and a pin projecting outwardly from the latch-post to temporarily support said flexible connection. 105

5. A dehorning structure embodying gate- 110 posts having slots or guideways at the upper end and latch-post side of the gateway, a gate hinged to the hinge-post, and provided with a recess in its upper edge, a lever hinged to the gate at the side of said recess nearest 115 the hinge-post and adapted to project through one of said slots or guideways and provided with an arched portion at its pivoted end, a block to form a stop for the lever when depressed, and means to lock said lever upon 120 said block. 115

6. A dehorning structure embodying gate- 125 posts having slots or guideways at the upper end and latch-post side of the gateway, a gate hinged to the hinge-post and provided with a recess in its upper edge, a lever hinged to the gate at the side of said recess nearest the hinge-post and adapted to project through 130 one of said slots or guideways and provided with an arched portion at its pivoted end, a

block to form a stop for the lever when depressed, and a locking-pin to engage the latch-post above said lever.

7. A dehorning structure embodying gate-posts having slots or guideways at the upper end and latch-post side of the gateway, a gate hinged to the hinge-post and provided with a recess in its upper edge, a lever hinged to the gate at the side of said recess nearest the hinge-post and adapted to project through one of said slots or guideways and provided with an arched portion at its pivoted end, a block to form a stop for the lever when depressed, a locking-pin to engage the latch-post above said lever, and a flexible connection between said pin and the latch-post side of the gateway.

8. A dehorning structure embodying gate-posts having slots or guideways at the upper end and latch-post side of the gateway, a gate hinged to the hinge-post and provided with a recess in its upper edge, a lever hinged to the gate at the side of said recess nearest the hinge-post and adapted to project through one of said slots or guideways and provided with an arched portion at its pivoted end, and a second lever hinged to the gate and provided forward of the same with a forwardly-projecting bowed portion.

9. A dehorning structure embodying gate-posts having slots or guideways at the upper end and latch-post side of the gateway, a gate hinged to the hinge-post and provided with a recess in its upper edge, a lever hinged to the gate at the side of said recess nearest the hinge-post and adapted to project through one of said slots or guideways and provided with an arched portion at its pivoted end, a second lever hinged to the gate and provided forward of the same with a forwardly-projecting bowed portion, and a bracket forming a support for the last-named lever between its bowed portion and free end.

10. A dehorning structure embodying gate-posts having slots or guideways at the upper end and latch-post side of the gateway, a gate hinged to the hinge-post and provided with a recess in its upper edge, a lever hinged to the gate at the side of said recess nearest the hinge-post and adapted to project through one of said slots or guideways and provided with an arched portion at its pivoted end, a second lever hinged to the gate and provided forward of the same with a forwardly-projecting bowed portion.

jecting bowed portion, a bracket forming a support for the last-named lever between its bowed portion and free end, and means to secure said last-named lever to the latch-post side of the gateway.

11. A dehorning structure embodying gate-posts having slots or guideways at the upper end and latch-post side of the gateway, a gate hinged to the hinge-post and provided with a recess in its upper edge, a lever hinged to the gate at the side of said recess nearest the hinge-post and adapted to project through one of said slots or guideways and provided with an arched portion at its pivoted end, a second lever hinged to the gate and provided forward of the same with a forwardly-projecting bowed portion, a bracket forming a support for the last-named lever between its bowed portion and free end, a pin rigidly projecting from the latch-post side of the gateway, and a flexible connection attached at one end to said side of the gateway and adapted to engage the last-named lever and said pin to lock the former reliably closed.

12. A dehorning-gate embodying gate-posts having slots or guideways at the upper end and latch-post side of the gateway, a gate hinged to the hinge-post, and provided with a recess in its upper edge, means to lock the gate closed, and a lever hinged to the gate at the side of said recess nearest the hinge-post and adapted to project through one of said slots or guideways and provided with an arched portion at its pivoted end.

13. A dehorning structure embodying gate-posts having slots or guideways at the upper end and latch-post side of the gateway, a gate hinged to the hinge-post, and provided with a recess in its upper edge, means to lock the gate closed, a lever hinged to the gate at the side of said recess nearest the hinge-post and adapted to project through one of said slots or guideways and provided with an arched portion at its pivoted end, and a second lever hinged to the gate and provided forward of the same with a forwardly-projecting bowed portion.

In testimony whereof I affix my signature in the presence of two witnesses.

MARSHALL H. BIDWELL.
